UNITED STATES PATENT OFFICE.

CHARLES H. CROWELL, OF BROOKLYN, NEW YORK.

CORRUGATED-BOARD CONTAINER AND BLANK THEREFOR.

Application filed June 19, 1922. Serial No. 569,354.

To all whom it may concern:

Be it known that I, CHARLES H. CROWELL, a citizen of the United States, and resident of the borough of Brooklyn, county of 5 Kings, city and State of New York, have made a certain new and useful Invention Relating to Corrugated-Board Containers and Blanks Therefor, of which the following is a specification, taken in connection 10 with the accompanying drawing.

This invention relates especially to shipping containers made of corrugated paper board in which the body of the container may advantageously comprise a three or 15 four sided blank having transverse creases between the sides and preferably having its edges rabbeted or stepped so as to form a projecting edge flange which comprises the outer facing of the paper board. This 20 stepped edge may be greatly reenforced by pasting thereon a seam or edge reenforcing tape of gummed cloth or paper which engages the inner facing of the corrugated board and also adhesively engages the cut 25 or rabbeted edge and the projecting edge flange so as to greatly strengthen this projecting flange against splitting action in case the cooperating member of the container is forced out against it. The body 30 blank may have secured thereto one or more free sealing flaps or tapes preferably having corner folding notches so that after the cooperating blanks or members of the container are assembled and glued or secured 35 in place, if desired, these sealing flaps may be pasted over the same to securely and strongly hold them in place and tightly close the container.

In the accompanying drawing which 40 shows in a somewhat diagrammatic way several illustrative embodiments of the invention:

Fig. 1 is a perspective view of an illustrative container.

Fig. 2 is a plan view of a blank therefor.

Fig. 3 is an enlarged sectional detail showing the form of edge joint and sealing members.

Fig. 4 is a similar sectional view where 50 transversely or cross-corrugated paper board is used for the container elements.

Fig. 5 is a plan view showing another form of blank, and

Fig. 6 is a perspective view showing a 55 container made therefrom.

The multiple sided blanks for these con-

tainers may be made of ordinary or cross-corrugated paper board and of course the size and proportions of the blanks are made so as to suit the particular size and character of container desired. As shown in Figs. 60 1 and 2 the container may be formed of a four-sided body blank having the transverse creases 6, 7, 8 formed therein between the adjacent sides and it is usually desirable to 65 have the corrugations run vertically or transversely of the length of this blank where single corrugated board is used for making the same. As shown more in detail in Fig. 70 3, the edge portion of the blank may advantageously be given a rabbeted or stepped form so as to leave a projecting edge flange 18 comprising the outer facing of the corrugated board to which the usual corrugated spacing member 17 is adhesively secured. 75 These edge portions may be greatly strengthened and reenforced by adhesively securing thereto seam reenforcing tape such as 15 which may be strong gummed paper tape which is pasted or glued to the inner facing 80 of the side 2 of the container and then across the corrugated spacing member to form the portion 14 of this reenforcing tape which may also form the securing reenforcing member 13 strongly secured to the outer 85 facing of the corrugated board the edge 11 of the tape preferably substantially coinciding with the upper or free edge of this flange 18. Both the upper and lower edges 90 11, 12 of the blank may be similarly provided with such a seam reenforcing tape and as shown in Fig. 3, any outward pressure on this rabbeted edge of the body blank which might be exerted by the cooperating top or other container member is largely 95 or wholly borne by this strong tape which to a considerable extent transmits such outward pressure to the inner facing of the corrugated board instead of forcing or splitting away the outer facing or edge flange 100 18. It is also advantageous to form the body blank in the factory where it is shaped and creased with attached sealing flaps such as 5, 5' which are glued to the outer facing 105 throughout the top and bottom edges of the blank at least so that when the other container members are put in place these sealing flaps may be brought down upon the top member, for instance, and successively sealed in place which strongly secures the top member in position and also forms a tight closure especially where the corner folding 110

notches extend only partway through the projecting edge of this sealing flap. It is also advantageous to provide a connector tape of gummed cloth or paper such as 9 which 5 may be secured to one end of the body blank at the factory and adhesively secured to the other end of this blank as shown in Fig. 1 when the container is made up and used. Fig. 4 shows a way in which such a seam 10 reinforcing tape may be used advantageously to strengthen a rabbeted edge or projecting flange in cross-corrugated paper board having two transversely arranged corrugated paper spacing members 17 adhesively 15 secured to the facing members such as 19, 22. One or both of these rabbeted edges may be provided with similar seam reinforcing tape such as the gummed paper tape 11, 13, 14, 15 adhesively secured to the 20 corresponding sides and edges of the rabbeted blank or container member so as to similarly prevent splitting when the adjacent cooperating container member is forced outward with respect thereto. 25 It is not of course necessary to have four-sided blanks for these containers in all cases and Figs. 5 and 6 show three-sided container blanks which may be interconnected so as to form a six-sided container in the manner 30 shown in Fig. 6. One of these blanks forms the sides or faces 23, 24, 25 of the container and another somewhat similar three-sided blank of the container forms the sides 23', 24' and 25', at least one of the blanks having 35 such sealing flaps as 5, 5', 26 and 29 to be pasted or secured to the adjacent edges of the other blank and hold all of the parts securely together in assembled position. All of the rabbeted edge flaps or portions 40 of the blank may be strengthened by seam reinforcing tape such as 27 which may be glued or pasted around the same as indicated in Fig. 5 so as to greatly strengthen these rabbeted edges against splitting. 45 This invention has been described in connection with a number of illustrative embodiments, forms, portions, parts, materials, arrangements and methods of manufacture and use, to the details of which disclosure 50 the invention is not of course to be limited, since what is claimed as new and what is desired to be secured by Letters Patent is set forth in the appended claims.

I claim—

55 1. The corrugated paper board shipping container comprising a four sided straight strip body blank of corrugated paper board having the corrugations arranged transversely of the length of the blank and 60 formed with transverse folding creases between the adjacent sides, said blank being formed with stepped edges in which the outer facing of the corrugated board constitutes a projecting edge flange, seam reinforcing tape adhesively secured to said

stepped edges to strengthen the same and minimize the splitting off of this flange under outward pressure, separate top and bottom members of corrugated paper board having the corrugations therein extending longitudinally of said members and transversely to the corrugations in the adjacent long sides of the container, said body blank having free sealing flaps pasted to the longitudinal edges thereof to be adhesively secured to the adjacent portions of said top and bottom members to secure them in place and form a substantially tight closure for the container.

2. The corrugated paper board shipping container comprising a four sided straight strip body blank of corrugated paper board and formed with transverse folding creases between the adjacent sides, said blank being formed with stepped edges in which the outer facing of the corrugated board constitutes a projecting edge flange, seam reinforcing tape adhesively secured to said stepped edges to strengthen the same and minimize the splitting off of this flange under outward pressure, top and bottom members of corrugated paper board, said body blank having free sealing flaps pasted to the longitudinal edges thereof to be adhesively secured to the adjacent portions of said top and bottom members to secure them in place and form a substantially tight closure for the container.

3. The corrugated paper board shipping container comprising a multiple sided straight strip body blank of corrugated paper board, said blank being formed with stepped edges in which the outer portion of the corrugated board constitutes a projecting edge flange, seam reinforcing tape adhesively secured to the inner facing of the corrugated board and along the adjacent stepped edge to strengthen the same under outward pressure and connected container members of corrugated paper board sealing tape being adhesively secured to the adjacent portions of said body blank and connected container members to secure them in place and form a substantially tight closure for the container.

4. The corrugated paper board shipping container comprising a multiple sided body blank of corrugated paper board, said blank being formed with stepped edges in which the outer portion of the corrugated board constitutes a projecting edge flange, seam reinforcing tape adhesively secured to the inner facing of the corrugated board and along the adjacent stepped edge to strengthen the same under outward pressure and connected container members of corrugated paper board.

5. The shipping container comprising a multiple side straight strip container blank formed of corrugated paper board, and

formed with folding creases and with stepped edges and seam reenforcing tape adhesively secured to the corrugated board adjacent said stepped edges to strengthen the projecting edge portions.

6. The shipping container comprising a multiple side container blank formed of corrugated paper board, and formed with stepped edges and seam reenforcing tape adhesively secured to the corrugated board adjacent said stepped edges to strengthen the projecting edge portions.

7. The multiple side straight strip container blank formed of corrugated paper board in which the corrugations adjacent the outer side of the blank are substantially transverse to the length of the blank, and formed with transverse folding creases and with stepped edges and seam reenforcing tape adhesively secured to the inner sides of the facing members of the corrugated board adjacent said stepped edges to strengthen the projecting edge flange against splitting off under outward pressure.

8. The multiple side straight strip container blank formed of corrugated paper board, and formed with transverse folding creases and with stepped edges and seam reenforcing tape adhesively secured to the corrugated board adjacent said stepped edges to strengthen the projecting edge flange against splitting off under outward pressure.

9. The multiple side container blank formed of corrugated paper board and formed with stepped edges and seam reenforcing tape secured to the inner sides of the facing members of the corrugated board adjacent said stepped edges to strengthen the projecting edge portions under outward pressure.

10. The container blank formed of corrugated paper board and formed with stepped edges and seam reenforcing tape secured to the corrugated board adjacent said stepped edges.

CHARLES H. CROWELL.
